UNITED STATES PATENT OFFICE.

ALONZO A. WARNER, OF NEW BRITAIN, CONNECTICUT, ASSIGNOR TO LANDERS, FRARY AND CLARK, OF NEW BRITAIN, CONNECTICUT, A CORPORATION.

VAPOR-LAMP.

No. 904,239.

Specification of Letters Patent. Patented Nov. 17, 1908.

Application filed April 14, 1908. Serial No. 427,047.

To all whom it may concern:

Be it known that I, ALONZO A. WARNER, a citizen of the United States, residing at New Britain, in the county of Hartford and State of Connecticut, have invented certain new and useful Improvements in Vapor-Lamps, of which the following is a specification.

My invention relates to improvements in vapor lamps and the object of my improvement is to improve the convenience and efficiency of the lamp in several ways as will be seen by the several features of construction hereinafter described.

In the accompanying drawing:—Figure 1 is a plan view of the main portion of my lamp, the wick tube being shown in horizontal section. Fig. 2 is a vertical section on the line *x x* of Fig. 1 of the lamp font and several of the connected parts, while other parts are shown in side elevation. Fig. 3 is a central vertical section of the wick tube, the wicking and surrounding wire cloth being shown in side elevation. Fig. 4 is a horizontal section on the line *y y* of Fig. 2, of the wick tube holder on the bottom of the lamp font, the spring catch or split ring and a portion of the bottom of the font being shown in plan view. Fig. 5 is a detached side elevation of the boss that forms the mouth of the lamp font and the shutter that slides up and down within the said boss. Fig. 6 is a horizontal section of the same on the line *z z* of Fig. 5. Fig. 7 is a horizontal section of the said boss on the line *s s* of Fig. 5, the shutter and its rack being removed therefrom.

The present invention consists of improvements in and additions to the vapor lamp disclosed and claimed in my application, Serial Number 387,820, filed Aug. 9, 1907.

A, designates the font having a central boss 8 within which boss the shutter 9 is arranged to be moved up and down. Surrounding the central boss 8 is an annular depression or priming recess 10 in which to place alcohol or other burning fluid for priming the lamp. The font is provided at one side with an internally threaded neck 11, that serves as the filling opening. Instead of closing this opening or neck by a solid plug I close the same by means of a small pump 12, the barrel of which is provided near its upper end with a threaded portion 13 that may be screwed into the said neck as shown, in which position the

nozzle 14 of the pump will be near the bottom of the font.

By pulling out the pump piston by means of the handle 15 when the pump is in the font, some of the fluid in the font may be taken up and upon removing the pump ejected into the priming depression 10, after which the pump may be replaced as a stopper.

The shutter operating pinion 16 is mounted on a shaft 17 that has its bearing in the tube 18, and is provided with a knob 19 in any ordinary manner of mounting like shafts and pinions. The shutter 9 is provided with an ordinary rack 20 which may be soldered or otherwise rigidly secured to one side of the shutter for engagement with the said pinion. The boss 8 is provided with an opening 21 Fig. 5, at one side to receive the said pinion, the said opening 21 being adjacent to the toothed edge of the rack. Adjacent to this opening and in position for being engaged by the back or untoothed edge of the rack, I form two triangular insets 22 in the boss, cutting the metal on that side of the said insets which are in line with the back of the rack so as to form inner shoulders on the boss opposite the plain edge of the rack to assist in holding the rack in engagement with the pinion. The flange 23 at the lower end of the central boss 8 is cut away on one side to provide an opening 24 for the rack to pass through, and I prefer to have one edge of this opening in the line of the shoulders formed by the insets 22.

The bottom of the font is provided with two upwardly projecting ribs 25 upon which is seated the wick tube holder 26. This holder is in the form of a short tube or socket and is provided with an internal groove 27 within which groove is seated a spring catch 28 in the form of a split ring, the said ring being a little less in diameter than the said groove so as to permit the said ring or catch to spring outwardly when receiving the lower end of the wick tube 29. The said lower end of the wick tube is provided with a rib or bead 30 for engagement with the said ring or catch. In order to insert the wick tube within its holder, its lower end is inserted therein and when the under side of the bead 30 engages the split ring or catch, the wick tube is forced downwardly to expand the said catch and let the bead pass by, after which the ring contracts

and lying just above the bead secures the wick tube against accidental displacement while at the same time it may be withdrawn by pulling it upwardly or outwardly with sufficient force.

As in my aforesaid application, I tightly close the upper end of the wick tube 29 by means of a cap 31 and I form the outlet 32, Fig. 3, of the wick tube near the mouth of the font as formed by the central boss 8. This outlet opens into a surrounding jet ring 33 having perforations or jets 34 in its top, the said jets forming the vapor outlets of the lamp. The jet ring as in my aforesaid application is of a size to fit and substantially fill the shutter 9. Above the jet ring the wick tube is substantially hexagonal in horizontal section, but with slightly depressed side faces 39, the angles of the several faces being extended far enough to substantially fill the shutter, that is, far enough to reach nearly to the inner wall of the shutter. The jets 34 correspond in number to the several side faces of the angular portion of the wick tube above the jet ring, and are located at about the middle of the said faces as shown in Fig. 1. Below the jet ring, the wick tube is enlarged so as to form an internal annular chamber 35 that extends downwardly a short distance, below which chamber the wick tube is of substantially the same diameter as it is within the jet ring. Instead of the loose rod shown in my aforesaid application, I encircle or partially encircle the wicking 36 with wire gauze 37, the same extending over that portion of the wicking that lies within the annular chamber 35, and up through the jet ring whereby the wicking is prevented from expanding to fill the annular chamber and also is held out of contact with the inside of the wick tube above and for a short distance below the said chamber so as to hold the wicking away from the wick tube from end to end of the said gauze.

If desired the meeting or confronting edges 38 of the wire cloth 37 may be turned in as shown. No fastening of the wire cloth or gauze, is necessary as it will stay in place by merely winding it about the wicking.

The shutter may be turned down far enough to bring its upper end nearly to the level of the top of the jet ring. When the lamp has stood idle for a time, the wicking becomes saturated and must be partially dried out before the lamp can be burned to the best advantage. Upon heating up the wick tube, the surplus liquid in the wicking above the jet ring will be forced downwardly. The wire gauze above the jet ring separates the wicking from the wick tube so that the liquid can thus flow down below the jet ring, while the annular chamber 35 forms a receptacle into which the liquid can flow and be taken up again by the wicking in due time.

This prevents the liquid from being forced out of the jets of the jet ring, notwithstanding the fact that these jets are quite a distance below the upper closed end of the wick tube. After the surplus liquid has thus been driven down and gas or vapor is generated within the upper part of the wick tube the said vapor can freely pass downwardly to the jet ring and burn at the jets. The shutter may be raised so far as to bring its upper end against the cap 31 for extinguishing the flame. It may also be stopped with its upper end intermediate its two extreme positions. By having the jet ring outside of the wick tube and the shutter outside of the jet ring, the shutter is necessarily of a larger diameter than the wick tube. By making a portion of the wick tube above the jet ring of an angular form I am enabled to bring the angles thereof closely to the side of the shutter so that when the shutter is partly elevated the several jets of the jet ring are separated from each other and the vapor may pass up between the outside of the wick tube and inside of the shutter and burn only at the upper end of the shutter. Were it not for these angles on the wick tube the flame would extend continuously upward from the jets.

I claim as my invention:—

1. In a vapor lamp, the combination of a font having a boss with a wick tube fitted in the said font and having an annular enlargement at a point within the font below the top of the said boss, a surrounding jet ring above the said enlargement and adjacent to the said boss, a wicking for the said wick tube and a sheet of metallic gauze surrounding a portion of the said wicking within the wick tube and extending longitudinally from a point near the lower end of the said enlargement upwardly above the top of the said jet ring.

2. In a vapor lamp, the combination of a font having a top with a wick tube mounted in the said font and having an annular enlargement extending longitudinally above and below the plane of the said top, and a wicking supported in position by the said wick tube at points above and below the said enlargement, the said wicking and tube having between them an annular space within the said enlargement.

3. In a vapor lamp, the combination of a wicking with a wick tube having an annular enlargement and a sheet of wire gauze interposed between the wicking and the confronting face of the said wick tube, the said sheet extending longitudinally of the wick tube over the said enlargement and supported at its opposite ends by the inner wall and the smaller diameter of the wick tube at each end of the said enlargement.

4. In a vapor lamp, the combination of a font with a tubular wick holder fixed in the bottom thereof, the said wick holder having an internal groove, a split ring mounted

within the said groove, and a wick tube having its lower end fitted to the said wick holder and provided with a peripheral bead for engaging the said split ring and for passing just below the said ring when the wick tube is fully in place.

5. In a vapor lamp, the combination of a font having a boss with a wick tube fitted therein and having a cap at its upper end and a surrounding jet ring some distance below the said upper end adjacent to the said boss, the said wick tube also having an angular portion extending upwardly from the said jet ring to the said cap with the corners thereof extending outwardly to nearly the size of the said jet ring, the said jet ring having a jet in its upper face for each of the faces of the said angular portion, and a shutter having its inner wall fitted to the exterior of the said jet ring, the said shutter being mounted to move up and down outside of the said jet ring and angular portion of the wick tube.

6. In a vapor lamp, the combination of a font having a boss with a wick tube fitted therein and having a cap at its upper end, a jet ring surrounding the said wick tube below the said upper end adjacent to the said boss, the said wick tube having an angular

portion extending upwardly from the said jet ring to the said cap with the corners thereof extending outwardly to nearly the size of the said jet ring, the said jet ring having a jet in its upper face for each of the faces of the said angular portion, and a shutter having its inner wall fitted to the exterior of the said jet ring, the said shutter being mounted to move up and down outside of the said jet ring and angular portion of the wick tube.

7. In a vapor lamp, the combination of a font having a mouth with a central boss fitted within the said mouth, a shutter arranged to move up and down within the said boss, a rack mounted on the said shutter to move therewith, a pinion and pinion shaft mounted on the said font for operating the said rack, and an inset portion in the side of the said boss with one edge of the said inset forming a shoulder opposite the plain edge of the said rack to assist in holding the said rack in engagement with the said pinion.
